UNITED STATES PATENT OFFICE.

JOHN A. BROOKS, OF DETROIT, MICHIGAN.

SPRAYING DEVICE.

Application filed June 12, 1925, Serial No. 36,577. Renewed March 14, 1927.

This invention relates to plumbing devices, but more particularly to automatic sprinklers for spraying lawns, shrubbery and the like.

- 5 Objects of the invention are to provide a new and improved spray head having adjustable features for directing the spray in any predetermined direction; to provide in conjunction with a spray head a replaceable 10 member for directing the spray in a definite predetermined direction; and to provide a sprinkling device having the new and improved features of construction, arrangement and operation hereinafter described.
- 15 A further object is to provide a spray head having new and improved features of construction for directing a stream of liquid in a defined path.

Illustrative embodiments of the invention 20 are shown in the accompanying drawings, in which,—

Figure 1 is a transverse section on the line 1—1 of Fig. 2; Fig. 2 is a longitudinal section on the line 2—2 of Fig. 1; Fig. 3 is a 25 vertical section of the device in operative position; Fig. 4 is a front elevation of the spray head; Fig. 5 is a section on the line 5—5 of Fig. 2; Fig. 6 is a front elevation of the spray head equipped with a spray 30 directing member for directing the spray to one side only of the device; Fig. 7 shows a spray head having a modified form of spray directing member for providing a semi-circular sheet of spray; and Figs. 8, 9 and 10 35 are perspective views of different forms of spray direction members.

The illustrative embodiment of the invention comprises a tubular conduit 1, which may communicate with any suitable source 40 of liquid supply, and integral therewith is an enlarged socket portion 2 having a flanged outer end 3. In the usual manner of sprinkling, the conduit and socket portion 2 may be placed in the ground with the 45 flange 3 substantially flush with the surface thereof, so that when not in use the device is not noticeable and does not interfere with mowing of the lawn.

Between the socket portion 2 and conduit 50 1 is a partition 4 having a passage 5, and 55 slidable in the passage 5 is a hollow stem 6 on which is formed at the lower end thereof an enlarged head 7 having a bevel portion 8 which is adapted to cooperate with 60 a bevel seat 9 on the partition 4 for provid-

ing a fluid seal between the head and partition when the stem is extended.

Connected to the outer end of the stem 6 is a sleeve 10 having a flange 11 at the lower end thereof and provided on the flange are 60 a plurality of grooves 12 which are spaced circumferentially from each other. For preventing rotation of the sleeve 10 a rib 13 is formed in the bore of the socket member 2 and extends axially thereof, this rib 65 projecting into one of the grooves 12.

Connected to the sleeve 10 is a cylindrical spray head 14 having in its lower portion a hollow bore 15, which communicates with the bore of the stem 6, and communicating 70 with the bore 15 is a recess or socket 16. The socket 16 consists of a cut-out portion which extends entirely across the spray head 14 and inwardly to the inner edge of the axial bore 15 of the head. An axially elongated recess 17 is opposed to the socket 16, and provided on the upper and lower edges of the recess 17 are grooves 18 which are 75 adapted to fit over the rib 13. It will be apparent that after the spray head 14 has 80 been tightly screwed on the sleeve 10, one of the grooves 12 in the flange 11 of the sleeve may be brought into registration with the grooves 18 of the spray head, thus preventing relative rotation of the parts although permitting sliding movement. The outer end of the spray head, is closed by an integral cap 19 which projects radially from the body of the head, and when the device 85 is not in operation this cap rests against a shoulder 20 on the socket member 2 with the outer surface of the flange 13.

For directing the liquid forced through the axial bore 15 in the form of spray, a removable member 21 is disposed in the socket 90 16 and is held in place by a screw 22 which projects through an elongated opening 23 into threaded engagement with the member 21, the head of the screw being disposed within the recess 17. The spray directing 100 member 21, as indicated in Fig. 8, may be semicircular in form, having a flat surface 24 which is adapted to abut against a portion of the head 14.

As shown, portions 25 may be cut out 105 from the inner face of the member with the upper edges inclined upwardly, so that when connected to the spray head 14, as shown in Fig. 4, the liquid will be forced in fine streams in opposite directions at approxi- 110

mately right angles to the axis of the spray head, and is useful for narrow strips of grass. If it is desired, however, to have a semi-circular sheet of spray, the member 21 may be reversed and the tapered circular surface 26 may then be disposed in close juxtaposition to the bore 15, this form being used along walks and driveways for sprinkling the grass but keeping the walks dry.

It is apparent that when the spray directing member is in the position shown in Fig. 7 with the apex of the semicircular surface in register with the axial passage 15, the wall of spray head 16 adjacent and at right angles to the passage 15 cooperates with the semi-circular tapering surface and flat parts of the connecting wall 17 on opposite sides of the tapering surface to deflect the stream of water or other liquid from the passage 15 in a defined path.

In the modified form of spray directing member, the cut-out portions 25 may be dispensed with, as shown in Figs. 7 and 9, and the member 21^a may be used simply for providing a semi-circular sheet of spray. Under some conditions it may be desirable to direct a stream merely to one side of the head, as for use at intersections of walks and driveways, and, as indicated in Fig. 10, the member 21^b may be formed with a single cut-out portion 25^a, it being understood that this manner is likewise reversible to direct the spray to the front as well as both sides.

In the operation of the device it will be apparent that the liquid entering the conduit 1 will act against the enlarged head 7, as well as against the spray directing member, and move the spray head 14 outwardly from the socket member 2, as shown in Fig. 3, and when the flow of liquid is turned off, the spray head 14 will automatically drop back into normal position within the socket member. Owing to the upright position of the parts, the water within the conduit returns to the supply line, thereby eliminating any danger of freezing in cold weather.

While I have shown and described a construction which is the best form known to me at the present time, it is to be understood that numerous changes in details of construction, arrangement and operation may be effected without departing from the spirit of

the invention, especially as defined in the 55 appended claims.

Having thus described my invention, what I claim as new and desire to secure by Letters Patent is:

1. In combination with a spray head having a water discharge passage, a pair of spaced substantially parallel walls on the head at the end of the passage and at substantially right angles to said passage, a wall connecting said pair of walls and disposed at substantially right angles thereto, a reversible spray member having a face formed to seat against either of said pair of walls and having a second face formed to seat against the connecting wall in either position of the spray member, and means extending through the connecting wall and into the spray member for connecting the spray member thereto, said spray member having spray-forming faces of differing 65 configuration presented to the stream issuing from said passage in the said two positions of mounting thereof.

2. A spray head according to claim 1, wherein one of said faces of the spray member comprises a substantially semicircular tapering water-engaging wall.

3. A spray head according to claim 1, wherein said second face of the spray member is formed with a cut-out forming a 85 downwardly tapering wall which in its operative position confronts the water passage to form a water channel between said cut-out and the connecting wall.

4. A spray head having an axial water discharge passage, a wall providing a water deflecting face disposed at right angles to the passage, a second wall extending outwardly from the first wall and at right angles thereto and located to one side of the water passage, and a water deflecting member extending outwardly from the second wall and having a substantially semi-circular tapering front surface with its apex in substantial register with the water passage, the portions of the second wall beyond the said member also affording water deflecting faces, whereby the two walls and the member all cooperate to direct the water.

In testimony whereof I have hereunto signed my name to this specification.

JOHN A. BROOKS.
